UNITED STATES PATENT OFFICE.

HERBERT TREVOR SHERWOOD, OF LONDON, ENGLAND.

CORSET.

976,608.

Specification of Letters Patent. Patented Nov. 22, 1910.

Application filed July 11, 1910. Serial No. 571,396.

To all whom it may concern:

Be it known that I, HERBERT TREVOR SHERWOOD, a subject of the King of the United Kingdom of Great Britain and Ireland, and resident of London, England, have invented a certain new and useful Improvement in Corsets, of which the following is a specification.

This invention relates to improvements in corsets of the kind in which laced incisions or slits and belts or straps are provided for adjusting the corset to suit the figure or to reduce the figure, and has for its object to insure that an unruffled surface shall always be presented in any position of adjustment and to dispense with the usual rigid web or elastic or cloth belt attachments.

In the accompanying drawings Figure 1 is a side elevation and Fig. 2 is a half sectional plan showing a corset equipped with the improvements. Fig. 3 is a part side elevation showing more clearly the means of adjustment.

Referring to the drawings, the incisions or slits A, which are preferably arranged one at each side of the busks B, are provided with a set of eyelets C on one side only of the line of incision A, a series of tapes or laces D passed through these eyelets being sewn or otherwise secured to the body of the corset at the other side of the line of incision, as at E. The tapes or laces D pass through a like series of eyelets F provided on a strip G arranged on the inside of the flaps H or the like which, as shown, are secured at each side of the busks B and are adapted to pass under straps I to the back of the corset without crossing. The other ends of each set of

laces D or the like are secured to a piece of elastic webbing K which in turn is secured to each flap H or the like.

In order to adjust the corset, the sides of each slit or incision A are drawn together or loosened as required by means of the tapes or laces D and the flaps or the like are adjusted in buckles L which may be secured, for example, to straps M extending from the back of the corset, the difference in tension being taken up by the elastic webbing K so that an unruffled surface shall always be presented. As shown, the flaps H may be formed with extensions h for attachment of suspension devices.

Having described my invention what I claim and desire to secure by Letters Patent of the United States is:

A corset comprising a body portion formed with an incision and with eyelets adjacent the line of incision on one side thereof, laces passed through said eyelets and secured at their ends to the body of the corset on the opposite side of the line of incision, a flap passing from the front to the back of the corset provided with a strip formed with eyelets through which said laces are also passed and an elastic web secured to the flap and to which the other ends of the laces are secured.

In testimony whereof I have signed my name to this specification in the presence of two subscribing witnesses.

HERBERT TREVOR SHERWOOD.
